PULP SCREEN PLATE

George W. Davis, Seattle, Wash.

Application November 27, 1929, Serial No. 410,048
Renewed April 23, 1934

4 Claims. (Cl. 92—30)

My invention relates to improvements in pulp screens of the form employed for screening wood pulp and other similar pulp which is used in the manufacture of paper.

5 These screens are usually formed of a plurality of flat screen plates of noncorrosive metal, each provided with a plurality of narrow parallel slots spaced relatively close together. These slots are very narrow, usually ranging from eight thousandths to twelve thousandths of an inch in width and are usually not more than three sixteenths of an inch apart. It is common practice to construct these screen plates from a single or integral piece of flat metal having the narrow slots formed therein by milling said slots from the bottom side of the plate. This leaves the end walls of the slots curved to conform to the shape of the milling cutter or circular saw with which they are cut, and results in the slots 15 being shorter on the top side of the bar than they would be if these slot ends could be cut straight through the plate. A serious objection to this method of forming the slots is that, by this method, the effective screening area of a 20 screen plate may be reduced as much as twenty percent below the maximum area possible of attainment. Another objection to milling the plates in this manner is that the curved and undercut ends of the milled slots form traps in 25 which pulp and solid matter may collect and thus further reduce the effective screening area of the plates. Another objection to this method of constructing the screen plates by milling from a solid metal plate is that it makes difficult the 30 overhaul and repair or reconstruction of the plates in case they become worn or badly clogged or broken, it being common practice to overhaul 35 plates of this type by re-rolling and re-milling them thus often making necessary a complete 40 and expensive overhaul job to correct a slightly worn or broken plate.

In accordance with my present invention I correct and overcome the objectionable features hereinbefore pointed out by making a pulp screen 45 plate out of a plurality of bars which are removably secured together in side by side parallel relation by tie rods to thereby form a screen plate which is easily disassembled for purpose of cleaning or repair or replacement of parts, said 50 bars being spaced apart by separate spacers which are short and which obstruct the slots for the least possible distance and which provide straight end walls for the slots thus avoiding the formation of traps wherein solid matter may collect. 55 Another object of my invention is to provide

a pulp screen plate which is plane on both the top and bottom and which has no frame members or other members projecting above or below the top and bottom planes of the bars and which is strong enough so that it is self supporting for 60 the purpose of handling, said screen plate being arranged to be placed in a pulp screen frame when in use and having inclined ends arranged to fit said frame.

A further object of my invention is to provide 65 a pulp screen plate in which the bars are of substantially T shape in cross section whereby pulsations of water and pulp upward against the bottoms of said bars from below will not tend to wedge the pulp into the slots as it might tend to 70 do in the case of wedge shaped bars.

These pulp screens are not of large size but are usually about three and one half feet long and not over twelve inches wide. The bars from which the screens are made are about three 75 eighteenths of an inch in depth and three sixteenths of an inch wide. These approximate dimensions are given to distinguish this screen from large heavy grate bars and like structures.

Other and more specific objects will be apparent from the following description taken in connection with the accompanying drawing.

In the drawing Figure 1 is a plan view of a fragment of a pulp screen plate constructed in accordance with my invention.

Fig. 2 is a sectional view of the same substantially on broken line 2—2 of Fig. 1.

Fig. 3 is a cross section on an enlarged scale on broken line 3—3 of Fig. 1.

Fig. 4 is a detached perspective view of one of 90 the grate bars.

Fig. 5 is a detached perspective view of one of the spacer plates.

Fig. 6 is a plan view on a small scale of an 95 entire screen plate constructed in accordance with my invention.

Fig. 7 is a fragmentary plan view on a smaller scale of a pulp screen in which the screen bars extend lengthwise instead of crosswise of the screen.

Fig. 8 is a fragmentary perspective view showing 100 an alternative means for securing the screen bars together by the use of tie bars fitted into notches in the ends of the screen bars.

Fig. 9 is a fragmentary perspective view of a 105 screen bar which is of T shaped cross section throughout its entire length.

Fig. 10 is a sectional view on a larger scale showing the spacing blocks used in connection with the screen bars shown in Fig. 8.

Referring to the drawing, throughout which like reference numerals designate like parts, Figs. 1 to 6 inclusive show a pulp screen plate made up of a plurality of bars detachably secured together so that they may be taken apart for overhauling, cleaning, repairing, or rebuilding. The screen bars are all of duplicate construction, and are shaped like a T bar in cross section each having a plane flat top flange or plate 10 and a 10 downwardly extending flange or rib 11. At both ends and at a location substantially mid way between the two ends, the screen bars are provided with thickened portions 12 which are flush with the sides of the top web 10 and are provided with perforations 13 through which tie rods 14 may be passed to secure said bars together to form a screen plate. These screen bars are preferably formed by side milling and leaving the thickened portions 12 the full width of the bar. 15 When the bars are assembled thin spacer plates 15 are inserted between the thickened portions 12 of the bars to maintain the bars in spaced apart relation and to form relatively narrow slots 16 through which the pulp may pass as it flows over the screen plates. The spacer plates 15 may be perforated or notched to fit over the tie rods 14. Nuts 17 may be provided on the tie rods 14 at one end for clamping all of the screen bars together. When the screen plates are thus assembled their top surfaces are all flush and in the same plane and their bottom surfaces are all flush and in the same plane and they are self supporting and do not need to be reinforced by any frame members in order to make them strong enough for the purpose of handling and shipment. When in use the screen plates are placed in a frame 18, as shown by broken lines in Fig. 2, and may be bolted down or held in place by wedge bars 19 which engage inclined ends 20 of the screen bars. Additional supporting members 19' may be provided under the screen bars. For cylindrical screens the screen bars are bent into circles or segments of circles.

The spacer plates have straight edges which form substantially vertical end walls 21 for the slots 16. These vertical end walls tend to prevent the formation of hard masses of pulp and solid matter in the ends of the slots and thus help to prevent clogging up and reduction of efficiency of the screen plate. If the ends of these slots are inclined or curved a substantial amount a trap is formed at the ends of the slots in which pulp and solid matter tends to collect.

Making the screen bars substantially T shape in cross section lessens the danger of the pulp being forced upwardly into the slots and clogging said slots due to the surge or pulsation of water below the screen, it being apparent that pulp driven up against the screen plate from below will have less tendency to pass into the slots where a T bar shape is used than it would if the space below the slots converged toward said slots and formed a wedge chamber for the pulp to be driven upwardly into. Due to the agitation and upward surging of the water below the pulp screens it is important that the bottom sides of the bars be correctly shaped as hereinbefore set forth.

In Fig. 7, I have shown a pulp screen plate in which the bars 22 are arranged lengthwise of the plate instead of crosswise and in which cross tie rods 23 are provided at frequent intervals. The construction of this pulp screen plate is otherwise similar to the construction of the screen plate hereinbefore described.

In Fig. 8 I show a perspective view of a fragment of a pulp screen plate in which the screen bars 24 are notched in the ends, as at 25, and a retaining bar 26 is placed in said notches and secured to the bars, as by brazing, to thus serve as a means of holding said bars in assembled relation.

In Figs. 9 and 10 I have shown a fragment of a pulp screen plate in which the bars 28 are T shape throughout their entire length and the spacers are in the nature of blocks 29 arranged to fit between the vertical flanges of the bars and having relatively thin fins 30 thereon arranged to fit between the edges of the horizontal flanges of the bars. The advantage of this form of construction lies in the fact that these bars 28 may be made by a process of rolling rather than by milling, thus cheapening the cost of construction and making it possible to form the bars out of more durable material.

It will be noted that the bars in the screen plates herein disclosed extend over the entire width or entire length of the plate thus avoiding joints or connecting means for the bars within the area of the plates and contributing to the formation of a stronger and more rigid and durable screen plate.

The screen plates may be quickly and easily taken apart for the purpose of cleaning or repair and worn or defective bars may be readily replaced with new ones. The use of the separate spacers simplifies the construction of the screen bars and makes it possible to provide vertical end walls for the slots and makes it possible to secure a maximum length of open slot in proportion to the length of the bar thus increasing the effective screening area on a screen plate of given size.

The foregoing description and accompanying drawing clearly disclose a preferred embodiment of my invention, but it will be understood that this disclosure is merely illustrative and that changes may be made within the scope and spirit of the following claims.

I claim:

1. In a multiple bar pulp screen plate, a plurality of bars of T shaped cross section throughout their entire length, having straight edges at both sides of their top flanges arranged to cooperate to form narrow slots, spacer arranged to be interposed at intervals between said bars to maintain said bars in spaced apart relation, said spacers having wider parts fitting between the bottom webs of said bars and narrower parts fitting between the top flanges of said bars, and tie rods for releasably securing a plurality of said bars together to form a screen plate.

2. A pulp screen plate embodying a plurality of relatively narrow bars disposed side by side in parallel relation, said bars having wider top flanges and narrower lower web portions, said narrower lower web portions being provided with thickened portions positioned at the respective ends and at a location spaced between said ends, said thickened portions being flush with the sides of said wider top flanges and having transverse holes therein, separable spacer plates of predetermined thickness positioned between said thickened portions and supporting said bars in spaced apart relation whereby narrow slots are provided therebetween, said spacer plates each having two edges formed at substantially right angles to each other, one of said edges being positioned flush with the top flanges of the adjacent bars and the edge at right angles thereto forming an end wall for the slot between the

adjacent bars, which end wall is perpendicular to the top flanges of the bars, said spacer plates each having openings in registration with the holes in said thickened portions and said spacer plates each being relatively short in length whereby a maximum length of slots is afforded, and tie rods extending through the thickened portions of said bars at the respective ends of the bars and at the location which is spaced between the ends of the bars whereby said bars are all secured together and the spacers whereby all of the bars are secured together at their ends 10 and at a location between their ends.

3. A pulp screen plate of the class described, embodying a plurality of relatively narrow bars disposed side by side in parallel relation, said bars having wider top flanges and narrower lower web portions, said narrower lower web portions being provided with thickened portions positioned at the respective ends of said bars and at a location spaced between said ends, said thickened portions being flush with the sides of 20 said wider top flanges and having transverse holes therein, separable spacer plates of predetermined thickness positioned between said thickened portions and supporting said bars in spaced apart relation whereby narrow slots are provided between said bars, said spacer plates each having two edges formed at substantially right angles to each other one of said edges being positioned flush with the top flange of the adjacent bars and the edge at right angles thereto forming 30 an end wall for the slot between the adjacent bars, which end wall is perpendicular to the top flanges of the bars, said spacer plates each having openings in registration with the holes in said thickened portions and said spacer

plates each being relatively short in length whereby a maximum length of slot is afforded, and tie rods extending through the thickened portions of said bars at the respective ends of the bars and at the location which is spaced between the ends of the bars whereby said bars are all secured together and a pulp screen plate which is self supporting without additional frame means is formed, said bars all being of equal depth with their top and bottom edges terminating in a 85 common plane whereby a pulp screen plate having two plane surfaces free from protruding members is afforded.

4. A multiple bar pulp screen plate, embodying a plurality of relatively narrow bars of T shape cross section disposed side by side in parallel relation, separable spacer members of predetermined thickness positioned between said bars and supporting said bars in spaced apart relation whereby narrow slots are provided between said bars, said spacer members each having two straight edges formed at substantially right angles to each other, one of said edges being flush with the top flanges of the adjacent bars and the edge at right angles to said flush edge being positioned between the adjacent bars and forming an end wall for the slot between the bars, which end wall is at right angles to the length of the bars, and tie rods extending through said bars and said spacer members whereby said 105 bars are detachably secured together to form a self supporting pulp screen plate capable of being dis-assembled for reconstruction.
